United States Patent Office

Des. 227,473
Patented June 26, 1973

227,473

CALCULATOR

George J. Lampel, Los Angeles, Calif., assignor to Citizen
America Corporation, Beverly Hills, Calif.

Filed June 5, 1972, Ser. No. 260,054

Term of patent 14 years

Int. Cl. D14—02

U.S. Cl. D26—5 C

Fig. 2

FIG. 1 is a perspective view of a calculator showing my new design;

FIG. 2 is a rear view thereof;

FIG. 3 is a top plan view thereof;

FIG. 4 is a right side view thereof; and

FIG. 5 is a front view thereof.

I claim:

The ornamental design for a calculator, as shown.
